UNITED STATES PATENT OFFICE.

FREDRIC C. WEIR, OF CINCINNATI, OHIO.

IMPROVEMENT IN RAILWAY-FROGS.

Specification forming part of Letters Patent No. 171,073, dated December 14, 1875; application filed May 11, 1875.

To all whom it may concern:

Be it known that I, FREDRIC C. WEIR, of Cincinnati, Hamilton county, State of Ohio, have invented an Improvement in Frogs and Frog-Joints, of which the following is a specification:

My invention relates more particularly to the class of reversible frogs, and is intended to remedy the pre-existing evils or defects in the use of this class of frogs; but it is also applicable, in part, to unreversible frogs and connecting-rails; and my invention consists, in the first part, in the provision of chairs for the ends of the frog, and the ends of the rails having seats or beds to receive and support said ends, and upwardly-projecting flanges extending on each side of the joint between the ends of the frog and rail, to break the joint and make a continuous bearing between the rails and frog, the chairs being of such construction that, while they may be used with a frog that is not made to reverse, they are particularly applicable to reversible frogs, and, by reason of the arrangement of the flanges, are adapted to give a firm support to the rails. My invention consists, in the second part, of the combination of the flanged chairs, the rails connected thereto, and connecting-bolts to firmly secure the rails to said flanges at the side, and thus dispense with the use of separate fish-plates. My invention consists, in the third part, in the peculiar construction of the frog, it being formed with cored compartments and a stiffening partition, for the purpose of lightening the frog without depriving it of the necessary strength. My invention consists, in the fourth part, in the peculiar construction of the frog, by which it is specially adapted for reversibility and continuous bearing in a simple way, by the provision of a gap or slot at the heel, cut entirely through, and adapted to fit over the tongue of the chair in either position.

Figure 1 is a perspective view of the frog and its chairs, the frog being lifted to expose the chairs. Fig. 2 is a perspective view of the frog in place in its chairs. Fig. 3 is a sectional perspective view of the frog, showing the manner in which it is cored.

A is the frog, formed, as shown, for reversibility, having a central web, *a*, and lugs *b*, for

attachment to the chairs, the web and lugs being so disposed, as shown, that the frog may lie on either side without affecting the relation between itself and the chairs or rails. One end of the frog has parallel sides *c c*, and the other end a gap or slot, *d*, the gap *d* and sides *c* also being so constructed as to permit the reversibility of the frog. C D are chairs, to support the ends of the frog; and E F, intermediate chairs, to support the middle of the frog. The end chair C is provided with a central upwardly-projecting flange or web, *e*, to fit the gap *d* and laterally support the frog at that end, and it is also constructed with beds *f* on each side of the flange, to vertically support the face of the frog and beds *g*, for lugs *b* of the frog to rest upon, the beds *f g*, when the frog is reversible, being in different planes. The chair D is provided with vertically-projecting flanges *h*, whose interior faces fit the sides *c c* of the frog, and is constructed with beds *i j*, in different planes, to support this end of the frog in the same way as the beds *f g* operate.

Reversible frogs used heretofore have been made to rest upon the ties of the track, and were not supported in chairs which received the rails, and consequently the proper relation between rails and frog was liable at any time to be disturbed.

In my device the chairs C D offer mutual support to the rails J and frog, and neither rails nor frog can be displaced independently one of the other, both necessarily having to move together. The flanges *e h* not only serve to laterally sustain the frog in the manner indicated, but I make them extend so far longitudinally beyond the ends of the frog as to embrace the sides of the rails J, and I permanently secure the ends of the rails to these flanges by bolts *k*, in the manner shown. This extension of the flanges also serves to break the joint between the rails and frog, and carry the weight of the cars over the joint.

The frog is cored into compartments *G*, divided by partition or vertical web *H*, the latter being, preferably, relieved from unnecessary weight by apertures *I*, formed by the core. This coring of the frog lessens its weight materially, without robbing it of the necessary strength, the central partition and the two

sides of the frog giving all the stiffness necessary in a vertical direction.

I claim—

1. The end chairs C D for a frog, having the flanges *e h*, to overlap the joint between the frog and rails, and laterally support the frog, substantially as and for the purpose specified.

2. A reversible frog having cored compartments G and partition H, substantially as and for the purpose specified.

3. A frog having parallel side faces *c c* at one end, and a gap or slot, *d*, at the opposite

end, for affording lateral support to the same, substantially as and for the purpose specified.

4. In combination with the chairs C D *e h* and rails J, the connecting-bolts K, connected and operating substantially as and for the purpose specified.

In testimony of which invention I hereunto set my hand.

FREDRIC C. WEIR.
